UNITED STATES PATENT OFFICE.

EUGRAPHUS RYKOVSKOFF, OF MOSCOW, RUSSIA.

CATTLE-CAR.

SPECIFICATION forming part of Letters Patent No. 657,454, dated September 4, 1900.

Application filed April 21, 1896. Serial No. 588,511. (No model.)

To all whom it may concern:

Be it known that I, EUGRAPHUS RYKOVSKOFF, a subject of the Emperor of Russia, and a resident of Moscow, Russia, have invented certain new and useful Improvements 5 in Railway-Cars for Cattle, of which the following is a specification.

This invention has relation to stock-cars, and more especially to two-storied or so-called 10 "double-deck" cars; and it consists in certain improvements hereinafter to be fully described.

So far as I am aware double-deck cars have before my invention not been constructed for 15 the accommodation on both decks of the larger stock, as cattle and horses, owing to the difficulty in obtaining the necessary clear space vertically without increasing the height of the car beyond the usual prescribed limits.

20 The object of my invention lies in the construction of the car-body relatively to the truck, whereby the required height of both decks is obtained without exceeding the usual prescribed limit of height of cars.

25 Referring to the accompanying drawings, Figures 1 and 1^a respectively show the left half of a stock-car embodying my invention in vertical section and the right half in elevation. Figs. 2 and 2^a, respectively, 30 show the lower and upper decks in horizontal section, part of the flooring in the latter figure being broken away; and Fig. 3 is a half cross-section and half elevation of the car.

The body of the car, which is or may be a 35 box-car, may be constructed in any usual manner, though I prefer to construct the framing F of metal and the paneling of wood, and said car-body may be supported from two or four wheel trucks, the former arrangement 40 being shown in the drawings.

In order that the required height of decks 45 may be obtained without increasing or greatly increasing the usual prescribed height of the car, I drop the lower deck-floor A quite considerably below the wheel-axles A² or as much as the track will permit and so as to obtain a clear height of about six feet three inches, which is sufficient for the largest kind of cattle and medium-sized horses, while for the 50 transportation of the larger class of horses the car-roof immediately above the feed-troughs can be sufficiently raised, and this

I do not deem necessary to illustrate, as it is a matter within the province of any car-builder. Both decks of the car are divided 55 transversely into separate stock-compartments, first, by means of the feed-troughs B for the lower deck and B' for the upper deck, and, secondly, by means of cross-beams c and 60 and narrow cross-partitions d, seated on said beams, which are arranged immediately above and extend along the center of the troughs and are provided with rings e to tie the stock to. In this manner the troughs are divided, so that stock on one side cannot interfere 65 with stock on the opposite side of the troughs, while there is a considerable space above the cross-partition d, which insures free circulation of air throughout the compartments.

The troughs B B' are raised above the deck-floors for obvious purposes, and the space E below them is utilized as a storage-space for provender, except, of course, the two troughs on the lower deck that lie immediately above the wheel-axles, the drop of the floor being 75 such as to bring these troughs to a sufficient elevation. Access is had to these storage-chambers from without through openings h h in the sides of the car, normally closed by 80 suitable doors.

Between the two center compartments of the upper story there is an attendant's compartment C, from which access may be had through doors D' to the adjacent stock-compartments, access being had to said compartment C, as well as to all of the stock-compartments, from without only through doors D, F, and F' and suitable iron steps b, secured to the sides of the car in a well-known manner. All of the stock-compartments 85 have separate doors except the two central compartments of the lower deck, access to which is had through a common doorway F'.

In the floor of the attendant's compartment C is an opening a, by means of which supervision can be had of the stock-compartments 95 of the lower deck, though these do not connect with said attendant's compartment by steps or ladder or the like.

Each of the stock-compartment doors has 100 in its upper panel two ventilating-openings f, which in cold or inclement weather can be closed by suitable slides. The doors for the compartments of the upper deck slide on rails

r, provided with suitable stops *r*² at opposite ends, there being a rail *r* for each two doors. The doors for the stock-compartments of the lower deck are hung from rails *R*², provided with similar stops at their ends. There are also intermediate stops *q* on rails *r* *R*² between each pair of doors to limit their movement toward each other in opening them, and in order to avoid accidental closing, as when the cars are loaded on a slight grade, I provide couplings consisting of a hook-bolt *i*² on the inner member of the door-frame of one door and a plate *i*⁴ on the like frame member of the adjacent door, said plate being provided with a staple to which the bolt *i*² may be hooked. By this means I am also able to keep the doors wide open either when the empty cars are standing in a yard or on a siding or while such empty cars are in transit from one place to another, thus affording excellent means for thorough ventilation.

In order to provide plenty of air and ventilation for the stock-compartments, I form openings *i* in each side of the car and on opposite sides of the troughs or in a line with the heads of the stock tied to these troughs. These openings are each provided with suitable registers for regulating ventilation or closing the openings altogether. In the drawings I have shown these registers as consisting of two perforated sliding shutters *g*, movable relatively to each other to bring their perforations more or less into or out of register with one another, said shutters also serving as a means for supplying the troughs with food taken from the chambers *E* underneath.

The floors *A* and *A'* of the lower and upper decks are provided with perforations *n* for the drainage of the liquid manure, that from the upper floor being collected on a sheet-metal ceiling *C'* for the lower deck, which is preferably channeled and arranged in such manner as to cause such liquid manure to flow to drain-pipes *p*, that extend down along the sides of the car in each stock-compartment and discharge near the bolsters 4 under the car.

The solid manure is removed from the several compartments through openings *o* in the lower-deck floor and *o'* in the upper-deck floor, which latter are immediately above the former, so that such manure can be removed through said lower openings *o*. These openings are or may be normally closed by trap-doors in very cold weather. Otherwise they act as ventilators.

For the purpose of watering the stock I provide a distributing system and connections whereby the stock on a train of cars may be simultaneously watered at watering-stations, the supply being taken from the usual watering-tanks that supply locomotives. There are two mains *H*, running lengthwise of the upper-deck floor along opposite sides of the car, whose terminals are con-

structed to receive either a flexible hose-coupling *I* *j* of well-known construction for connecting a line of mains of a train in series or to receive a valved discharge-spout *P* for application to the terminal of the last main of a line of such, which serves not only as discharge for water, but more especially as an air-vent in supplying a line of mains with water, and, lastly, to receive a flexible hose-coupling *M* *N* *O* for application to the initial of the first main of a line of such and for coupling to the discharge of a supply or watering tank, such couplings being well known, and as they may be of any desired construction it will not be necessary to enter into a detailed description thereof. To each of these mains *H* are tapped vertical distributing-pipes *K* and *K'*, communicating with each other, there being of course two such pipes for each stock-compartment, and they are provided with stop-cocks *L* and *L'*, respectively. The pipes *K* dip into the troughs *B* of the lower deck, while the pipes *K'* rise through the bottom of the troughs *B'* of the upper deck and have hoods to prevent fodder entering the same. It will readily be seen that when a main *H* of the forward car, for instance, is coupled to a water-tank and the air-vent *P* of the main of the last car opened, as well as the stop-cocks *L* and *L'*, water will be supplied to the troughs throughout the train, the air-vent being closed as soon as water begins to flow therethrough. On the other hand, after the stock has been watered the water from the upper troughs can be drained into the lower troughs and thence discharged through waste-pipes *l*, normally closed by plugs *m*.

Having thus described my invention, what I claim as new therein, and desire to secure by Letters Patent, is—

1. A double-deck stock-car, comprising a metallic under body, a metallic underframing for the upper compartment forming the top of the lower compartment, trucks between the side sills, flanged bolsters whose flanges are adapted to rest on the ends of the trucks and support the car, substantially as set forth.

2. A double-deck stock-car, comprising a metallic underframe, a metallic underframing for the upper compartment, metallic posts connecting the side sills of the two framings, flanged bolsters on the lower framing adapted to rest on the trucks, and diagonal tension members from the line of support to the side sills of the framings, substantially as set forth.

In testimony whereof I have signed my name to this specification in the presence of two subscribing witnesses.

EUGRAPHUS RYKOVSKOFF.
